UNITED STATES PATENT OFFICE

ARTHUR LAWRENCE, OF CHICAGO, ILLINOIS.

ТИЛТИНГ БЕД-СРІНГ.

No. 857,353.

Specification of Letters Patent.

Patented June 18, 1907.

Application filed January 25, 1907. Serial No. 354,053.

To all whom it may concern:

Be it known that I, ARTHUR LAWRENCE, a citizen of the United States of America, and a resident of Chicago, in the county of Cook 5 and State of Illinois, have invented certain new and useful Improvements in Tilting Bed-Springs, of which the following is a specification.

The main objects of this invention are to 10 provide an improved form of bedstead and tilting spring arranged to permit the spring and mattress to be readily tilted on the bedstead to a position which will permit of conveniently sweeping or cleaning the floor under 15 the bed without moving the bedstead; to provide simple and convenient means for hinging bed-spring frames of common structure to bedsteads, without necessitating changes in the structure of either the spring- 20 frame or bedstead; to provide a simple and convenient device for holding the unhinged side of the spring-frame on a proper level with the hinged side when the spring is in the horizontal position when the bed spring is 25 raised. These objects are accomplished by the device shown in the accompanying drawings, in which:

Figure 1 is a perspective view of a bedstead and tilting spring constructed according to this invention. Fig. 2 is a section of one of the clamps and stops secured to the movable side of the bed-spring. Fig. 3 is a section on the line 3—3 of Fig. 4, showing one of the clamps securing the hinged side of the 35 bed-spring to the side rail of the bed. Fig. 4 is a top plan of the clamp and rails shown in Fig. 5, the rails being partly broken away. Fig. 5 is a vertical section through the clamps 35 and rail 34, showing the arm 33 of 40 the spring 32, partly broken away, and in the position indicated by the dotted lines 37 in Fig. 1.

In the device shown, the bed posts 1 have thereon the usual socket castings 2, to which 45 the side rails 8 and 22 are attached in the usual manner. The side rail 8 is clamped to the rail 9 of the bed spring frame, by means of the clamps, consisting of the members 10 and 12. The arms 10 and 12 are made to fit 50 the angle iron of usual form which is used for forming the side rails 8 and 9. The upper end of the clamp is turned over at 11 to engage the rail 9. The lower end has a similar hooked end 11 for engaging the rail 8. The 55 ends 11 of the clamps are made to fit loosely

over the edges of the rails 8 and 9 so that the clamps can be readily attached to and removed from the rails. The horizontal part of the member 10 has a slot 17 therein, with a bolt 13, which, with the washer 18 and nut 60 19, serves to hold the clamp securely on the side rail 8. The vertical part 12 of the other clamp has therein a slot 17, similar to the slot 17 in the part 10, and has a bolt 13 seated in said slot. The head 16 of the bolt 65 and washer 14 are drawn up by the nut 15 to bear against the vertical part of the rail 9, and serve as an adjustable clamping device or attaching member for holding said clamp in rigid position on the rail. The slots 17 70 to permit these clamping devices to be adjusted to rails formed of different widths of angle iron.

The heads 16 of the bolts 13 each acts as and is a clamp jaw, coacting with the parts 12 and 10 respectively. It will be understood that one of the clamp jaws of each pair, namely, the nut 15 or 19, has both a vertical and a horizontal adjustment relatively to its companion jaw which is the head 16 in one case or the slotted part of member 80 10 in the other.

The depending vertical part of the arm 10 prevents the clamp from being shifted from side to side of the rail 9. One of the arms of the clamp 10 is provided with perforated ears 85 3 to which the tubular part 4 of the other arm of said clamp is pivotally connected by means of the bolt 5 having thereon the nut 20.

The clamps 21 are attached to the side rail 22 of the spring in similar manner as the 90 clamps 10 are attached to the side rail 9. The lower part or projection 23 of the clamp 21, however, does not have a depending part extending along the outside of the side rail 24. This part 23 serves merely as a stop for holding the spring the proper distance above the rail 24 to support said spring in the horizontal position. The bolt 25 has a head 16 and an arm 26 secured to its outer end. This arm serves in connection with the movable 100 finger 27 for clamping the bed clothes and mattress upon the spring frame. Each of the end rails 28 and 29 of the bed spring frame has attached thereto a clamp 30 to which is pivotally secured the arm 31 of the spiral 105 spring 32. The arm 33 of said spring is pivotally secured to one of the end rails 34 of the bedstead by means of the clamp 35.

The operation of the device is as follows: The bed spring frame will be attached to the 110

side rail 8 by means of the clamps formed of the members 10 and 12. The springs 32 are of suitable strength to hold the bed-spring frame in the position shown in Fig. 1, but not of sufficient strength to prevent the bed-spring frame from resting in the horizontal position after it has been pulled down to said position. When in such horizontal position, the springs 32 will move to the position indicated by the dotted lines 37. Said springs, when in such position, with their arms 31 and 33 lying along each other, will offer less resistance than when said arms are in alignment and will therefore aid in permitting the spring frame to rest in the horizontal position. The leverage of the spring frame when in the horizontal position will also aid in counteracting the effect of the springs 32. When in a vertically disposed position, said spring frame is supported mainly on its hinged end at the rail 8, and therefore requires but slight support to prevent it from dropping to the horizontal position. The spring-arm 33 has its lower end bent to form a stop 36 which bears against the under surface of the rail 34 and limits the downward movement of the arm 33 to a position above the floor indicated by the dotted lines 37.

The mattress and bed clothes may be readily clamped by pushing the finger 27 down upon the rod 26, the finger being held down by leverage and friction on the rod 26. The function and operation of the finger 27 is the same as that of similar devices used heretofore at the lower ends of folding beds. The rod 26 and finger 27 will be used to clamp the bed clothes only when it is desired to raise the spring to the position shown in Fig. 1. At other times, said rod will be turned down to a horizontal position along the side rail 22.

What I claim as my invention and desire to secure by Letters Patent is:

1. The combination of a bedstead having a side rail, a bed-spring frame, a pair of adjustable clamp jaws removably engaging one of the side rails of the bedstead, and an attaching member hinged to said clamp jaws and secured to the bed-spring frame, one of said clamp jaws having both a vertical and a horizontal adjustment relatively of its companion jaw.

2. The combination of a bedstead and a bed-spring having adjoining side rails on each side, one side rail of said bed-spring having a hinge connection with the adjacent side rail of the bedstead, and a pair of adjustable clamp jaws removably engaging the opposite side rail of the bed-spring, one of said clamp jaws being provided with a projection adapted to bear upon the adjacent side rail of the bedstead and thereby support the bed-spring in normal position, and one of said clamp jaws having both a vertical and a horizontal adjustment relatively of its companion jaw.

3. The combination of a bedstead and bed-

spring frame, each having side rails, a pair of adjustable clamp jaws removably engaging one of the side rails of the bedstead and a second pair of adjustable clamp jaws hinged to the first pair and removably engaging the adjoining side rail of the bed-spring frame, one of the clamp jaws of each pair having both a vertical and a horizontal adjustment relatively of its companion jaw.

4. The combination of a bedstead and bed-spring frame, each having side rails, a pair of adjustable clamp jaws removably engaging one of the side rails of the bedstead and a second pair of adjustable clamp jaws hinged to the first pair and removably engaging the adjoining side rail of the bed-spring frame, one of the clamp jaws of each pair having an adjustment relatively of its companion jaw in two different planes at an angle to each other.

5. The combination of a bedstead and a bed-spring frame, having adjoining side rails on each side, each of said rails being formed of angle iron, a clamp connecting the adjoining rails on one side, said clamp consisting of a pair of angular arms, one of said arms being adapted to engage two faces of the side rail of said bed-spring, and the other of said arms adapted to engage two faces of the side rail of said bedstead, each of said arms being provided with an adjustable clamping member adapted to secure said arm against shifting upon the rail engaged thereby, said arms having a hinge-connection adapted to permit the bed-spring frame to be swung on such connection from a horizontal toward a vertical position.

6. The combination of a bedstead and a bed-spring frame, each having adjoining side rails on one side, said rails being formed of angle iron, a clamp connecting said adjoining rails and comprising two angular parts hinged together to form a widened W in cross-section, with the arms of said W at substantially right angles to each other, and an adjustable clamping member co-acting with each of said angular parts for rigidly securing said angle irons to said parts.

7. In a device of the class described, the combination of a pair of angle iron rails with a clamping member consisting of two angular arms pivotally connected together, and adapted to pivotally and detachably connect said rails, each of said arms having a slot extending at an angle to the axis of said pivotal connection, a bolt seated in, and adjustable lengthwise of each of said slots and carrying clamping members adapted to bear against one face of the slotted member, and against the opposite face of one of said rails.

8. In a device of the class described, the combination of a pair of angle iron rails, with a clamping member consisting of two angular arms hinged together, said arms each having one of its ends hooked and adapted to engage

one edge of one of said rails, and adjustable jaws on said members adapted to engage the opposite edges of said rails.

9. The combination of a bedstead and a bed-spring frame pivoted together at one side and provided with end rails, clamps removably engaging said end rails of the bedstead and the spring frame respectively, a pair of spring arms each pivotally secured to one of said clamps and said arms being connected at

their meeting ends by a spring adapted to normally extend said arms so as to hold the bed-spring frame in a raised position on its pivotal connection.

Signed at Chicago this 23rd day of January, 1907.

ARTHUR LAWRENCE.
